SWAB

Filed July 2, 1924

Fig. 3 Inventor
Frank W. Leidecker
By Still, Borch & West

Atty.

UNITED STATES PATENT OFFICE.

FRANK W. LEIDECKER, OF TULSA, OKLAHOMA.

SWAB.

Application filed July 2, 1924. Serial No. 723,613.

To all whom it may concern:

Be it known that I, FRANK W. LEIDECKER, a citizen of the United States, residing at Tulsa, in the county of Tulsa and State of Oklahoma, have invented a certain new and useful Improvement in Swabs, of which the following is a full, clear, and exact description, reference being had to the accompanying drawings.

10 This invention relates to improvements in what are known as swabs that are used for lifting a quantity of liquid from the casings or tubings of deep wells, such as oil wells, and for agitating the liquid in the bottoms 15 of the wells for the purpose of producing further or freer flow.

The main objects of the invention are:

First, to provide a swab that, in a contracted condition, may be easily and quickly 20 lowered into the casing or tubing, the fluid passing freely through and about the swab as the latter descends;

Second, to provide a swab that, upon being raised within the casing or tubing, 25 will expand against the wall thereof, the expansion of the swab being caused by internal pressure created by the weight of liquid above the swab, whereby the liquid is prevented from passing between the swab 30 and the wall of the casing or tubing;

Third, to provide, in a swab of the foregoing nature, means for automatically relieving the internal pressure and permitting fluid to pass the swab in the event that the 35 weight of liquid above the swab is so great as to impose undue strains upon the swab and swab-operating mechanism, or too great a friction between the swab and tubing or casing, such as might mutilate or otherwise 40 injure the packing element of the swab; and

Fourth, to provide adjusting means for varying the pressure at which the relief means becomes effective.

Further and more general objects are to 45 provide a highly efficient swab of the foregoing character that is very strong and durable and yet is comparatively simple and inexpensive of manufacture and that may be readily assembled and disassembled for the 50 purposes of inspection and replacement of parts.

These objects, with others hereinafter appearing, are attained in the construction

illustrated in the accompanying drawing wherein Figs. 1 and 2 are each a central vertical section through a part of a well casing or tubing in which is shown, in similar section, my improved swab, the first view representing the parts in the positions they occupy when the swab is descending, and the latter showing them in the positions they occupy when the swab is ascending; Fig. 3 is a fragmentary view, similar in character to the preceding views, showing the pressure relief means of valve in pressure relieving or open position; and Figs. 4, 5 and 6 are sections on the respective lines 4—4, 5—5 and 6—6 of Fig. 1.

In practice, the swabs are made in sizes to fit well casings and well tubings of different diameters. What is designated 1 may be considered either a well casing or well 70 tubing.

The swab comprises a central hollow stem or body 10 that is externally threaded at its opposite ends. A ball check valve is applied to the upper end of the stem or body 10 and the same comprises a cage 11 which encloses a ball valve 12 that is adapted to engage a seat 13, shown as clamped between 75 a shoulder 14 of the cage 11 and the upper end of a tubular member 15 which is externally threaded for application to the lower end of the cage 11 and is internally threaded 80 for application to the upper end of the stem or body 10. A swivel 18, having a head 19 at its lower end, is adapted to be inserted upwardly through the cage 11 and extended through the neck portion 20 thereof. The swivel is held within the neck portion of the cage by a nut 21 that is applied to its upper end. A washer 22 of suitable material, such as brass, is interposed between the head 19 and a shoulder 23 to insure easy rotation of the swivel. The swivel terminates at its upper end in a threaded pin 25 which is preferably designed to fit the sockets or boxes of standard sucker rods or other operating equipment, the lower end of a sucker rod being indicated at 26 in the drawing.

The expandable packing element or piston of the swab is designated 28 and the same is constructed of suitable material, such as rubber, and is reinforced at its ends by embedded elements designated 30 and shown 105 as having the form of coil springs. Heads

32 and 33 are applied to the opposite ends of the packing element or piston 28, and the one designated 33 is internally threaded so that it may be screwed up along the lower end of the stem or body 10. Threaded on the upper end of the stem or body is a nut 35 having a series of perforations 36 (see Fig. 5). The nut 35 is screwed down to a position adjacent the upper head 32. The head 32 is shown as having a series of passageways 38 which open into the space between the stem or body 10 and the packing element or piston 28. The lower head 33 is also provided with passageways or ports 39 which are normally closed by a valve 40, in the nature of a washer or ring, which is held seated against the underneath face of the head 33 by a spring 41 which is adapted to be compressed to any desired degree of tension between said valve and an abutment 42, in the nature of a nut, that is threaded to the lower end of the body or stem 10 and is adapted to be held against turning with respect thereto by a set screw 43 which has 25 its inner end reduced and adapted to enter a slot 44 in the wall of the stem or body.

As the swab is lowered into the casing or tubing in the presence of liquid, the parts assume the positions shown in Fig. 1 and 30 the liquid passes upwardly about the swab and through the hollow stem or body 10, as indicated by the arrows in Fig. 1, the ball valve 12 rising from its seat to allow a free passage of the liquid past the same. When 35 the direction of movement of the swab is reversed the parts take the positions and acquire the conditions illustrated in Fig. 2. Ball valve 12 drops to its seat and prevents the passage of fluid downwardly through the 40 stem or body 10. A part of the liquid above the swab enters through the holes 36 of the nut 35 and through the passageway 38 of the head 32 into the interior of the packing element of piston 28, expanding the same into 45 contact with the wall of the casing or tubing 1. If the tension of the spring 41 is equal to or greater than the weight of the liquid above the swab, the parts retain the positions shown in Fig. 2 as the swab is raised to elevate the column of liquid above it. However, should the weight of this liquid be 50 greater than the pressure of the spring 41, the valve 40 will recede from its seat, as shown in Fig. 3, permitting a quantity of 55 liquid to pass through the interior of the packing element or piston, the liquid continuing to pass the valve 40 until the pressure of the spring 41 balances the weight of the liquid above the swab, when the relief valve 60 40 will close and the swab operate as above described.

It is clear from what has been stated above that the abutment or nut 42 may be adjusted along the stem or body 10 to vary the tension of the spring 41 thereby to determine

how great a weight of liquid may be lifted by the swab before the relief valve opens.

Attention is also called to the fact that by reason of the design and method of mounting the seat 13 of the ball valve 12 said seat may be reversed so as to double its life.

Having thus described my invention, what I claim is:

1. A swab of the character set forth comprising a hollow body, a valve for preventing a downward flow and permitting an upward flow of fluid through said body, an expansible piston surrounding the body and enclosing a chamber that is open at top and bottom, and a valve for controlling the passage of fluid through the open bottom of the piston. 75
80

2. A swab of the character set forth comprising a hollow body, an upwardly opening valve for controlling the passage of fluid through said body, an expansible piston surrounding the body and enclosing a chamber that is open at top and bottom, and a downwardly opening valve for controlling the passage of fluid through the open bottom of the piston. 85
90

3. A swab of the character set forth comprising a hollow body, a valve preventing a downward flow and permitting an upward flow of fluid through said body, an expansible piston surrounding the body and enclosing a chamber that is open at top and bottom, a valve for controlling the passage of fluid through the open bottom of the piston, and adjustable means tending to retain the last mentioned valve closed whereby said valve may be caused to open at varying degrees of pressure. 95
100

4. A swab of the character set forth comprising a hollow body, heads applied to and spaced longitudinally of said body, an expansible sleeve supported by and between said heads, said heads having passageways which open into the interior of said sleeve, an outwardly opening valve controlling the passage of fluid through the passageways of the lower head, and a valve preventing a downward flow of fluid through the hollow body and permitting an upward flow therethrough. 105
110
115

5. A swab of the character set forth comprising a hollow body, a valve preventing a downward passage of fluid through said body and permitting an upward passage therethrough, an expansible piston surrounding said body, there being passageways for the access of fluid from above the swab to the interior of said piston, the lower end of said piston being provided with a port through which the fluid may escape from the interior of the piston, a valve seating upwardly against the piston for closing said port, an abutment sustained by the body below said valve, and a spring interposed between said abutment and the valve. 120
125
130

6. A swab of the character set forth comprising a hollow body, a valve preventing a downward passage of fluid through said body and permitting an upward passage therethrough, an expansible piston surrounding said body, there being passageways for the access of fluid from above the swab to the interior of said piston, the lower end of said piston being provided with a port 10 through which the fluid may escape from the interior of the piston, a valve seating upwardly against the piston for closing said port, an abutment adjustably sustained by the body below said valve, and a spring interposed between said abutment and the valve. 15

7. A swab of the character set forth comprising a tubular body, a head surrounding said body and spaced upwardly from its lower end, said head having an outlet port, a second head surrounding the body and spaced upwardly from the former head, an expansible sleeve of packing material supported by and between said heads, there being passageways for the access of liquid to the interior of the sleeve from above the swab, an annular relief valve surrounding the lower end of the body and arranged to seat against the underside of the first mentioned head and close the port thereof, an abutment adjustable along the lower end of the body, a spring surrounding the body and confined between said abutment and the aforesaid valve, and a valve preventing a downward flow of fluid through the body and permitting an upward flow therethrough. 30

8. A swab of the character set forth comprising a tubular body, a head surrounding said body and spaced upwardly from its lower end, said head having an outlet port, a second head surrounding the body and spaced upwardly from the former head, an expansible sleeve of packing material supported by and between said heads, there being passageways for the access of liquid to the interior of the sleeve from above the swab, an annular relief valve surrounding the lower end of the body and arranged to seat against the underside of the first mentioned head and close the port thereof, an abutment applied to the lower end of the body, a spring surrounding the body and confined between said abutment and the aforesaid valve, and a valve preventing a downward flow of fluid through the body and permitting an upward flow therethrough. 50

9. A swab of the character set forth comprising a tubular body, a head surrounding the body and spaced upwardly from the lower end thereof, a second head surrounding the body and spaced above the former head, an expansible sleeve of packing material supported by and between said

heads and spaced from the tubular body, said heads having passageways opening into the interior of the sleeve, an annular valve member surrounding the body and adapted to be seated against the underside 70 of the first mentioned head, an abutment carried by the lower end of the body, a spring surrounding the lower end of the body and confined between said abutment and said valve, an upwardly opening check 75 valve including a cage that is applied to the upper end of the body, and a swivel attached to the upper end of the cage and incorporating means for the application of operating equipment. 80

10. A swab comprising a hollow tubular body that is externally threaded at top and bottom, an abutment threaded onto the lower end of the body, a coil spring surrounding the body and resting upon said abutment, an annular valve sustained by said spring, a head screwed onto the lower end of the body above said valve and having ports controlled by said valve, a second head surrounding the body and spaced upwardly from the former head, the latter head having passageways, an expansible sleeve of packing material supported by and between said heads, a member threaded downwardly over the upper end of the sleeve against the second mentioned head and having holes which register with the passageways of said head, an internally and externally threaded member applied to the upper end of the body, a ball valve cage internally threaded at its lower end and applied to the last mentioned member, said cage having a shoulder opposed to the upper end of said member, a reversible valve seat clamped between said shoulder and said member, a ball within the cage that is adapted to engage said seat, and a pin swiveled within the upper end of the cage and to which is adapted to be connected operating equipment. 100

11. A swab of the character set forth comprising a hollow body, heads applied to and spaced apart longitudinally of said body, the opposed surfaces of said heads having channels, an expansible sleeve of packing material disposed between said heads and having its ends confined within said channels, said heads having ports, a valve controlling the port of the lower head, and a second valve for preventing a downward flow of fluid through the hollow body but permitting an upward flow therethrough. 115

12. A swab of the character set forth comprising a hollow body that is threaded at its opposite ends, ported heads applied to and spaced apart longitudinally of said body, one of said heads being threaded on the body, an abutment threaded onto the body and arranged to be engaged by the other

head thereby to prevent separation of the heads beyond a given distance, the opposed surfaces of the heads having channels, an expandible sleeve of packing material supported by and between said heads and having its ends within said channels, a valve controlling the port of the lower head, and

a second valve preventing a downward flow and permitting an upward flow of fluid through the hollow body. ¹⁰

In testimony whereof, I hereunto affix my signature.

FRANK W. LEIDECKER.
